UNITED STATES PATENT OFFICE.

WILLIAM SWALLOW, OF ROYTON, ENGLAND.

FLAME-SPREADER.

1,098,647.

Specification of Letters Patent.

Patented June 2, 1914.

Application filed August 14, 1913. Serial No. 784,761.

To all whom it may concern:

Be it known that I, WILLIAM SWALLOW, subject of the King of Great Britain and Ireland, and resident of Royton, Oldham, in 5 the county of Lancaster, England, have invented certain new and useful Improvements in Flame-Spreaders, of which the following is a specification.

My invention relates to improvements in 10 or in connection with burning-off lamps used by painters, though the improvements are equally applicable to similar lamps employed by plumbers and others, the object being to provide an improved form of burner nozzle 15 for attaching to the lamp burner tube of that type whereby the flame may be spread or be concentrated in accordance with the character of the work being operated upon.

This invention consists in the novel construction and combination of the parts hereinafter fully described and claimed.

In the drawings, Figure 1 is a side view of a spreading nozzle used in carrying out this invention. Fig. 2 is an end view, and Fig. 25 3 is a plan view of the same. Fig. 4 is a longitudinal section through the nozzle provided with a regulating plate according to this invention, Fig. 5 is a side view, and Fig. 6 is a plan view, of the regulating plate. 30 Figs. 7 and 8 are plan views showing modifications of the regulating plate.

In accordance with my invention I provide a nozzle having a tubular portion *a* of tapered formation at *b* internally to fit 35 the burner tube of a burning-off lamp or the like, the tapered formation allowing of the nozzle fitting different diameters of burner tubes. The outer end of the nozzle is fan-shaped, as shown in Fig. 1 and is 40 adapted to leave a correspondingly shaped chamber *c* within it opening into a slot *d* or elongated hole so that the Bunsen flame issuing from the nozzle is of a flat type and somewhat fish-tailed when looked at in the 45 direction of Fig. 1. In this way a flame which is greatly spread can be formed and thus cover a greater surface of the structure being operated upon by the flame. The nozzle can be used with the slot *d* arranged 50 horizontally or vertically or at any angle desired by merely turning the nozzle around on the burner tube.

The slot *d* shown in Figs. 1 to 4 is of substantially standard size but in order to enable a thinner flame to be produced or one 55 which is not spread so much or again one which may be of cylindrical formation I employ detachable plates such as those shown in Figs. 5 to 8. My invention is carried out satisfactorily by forming the end of 60 the nozzle with undercut flanges *e* and by making the plate *f* with correspondingly-shaped flanges *g*. The plate is of curved formation in side elevation as shown in Fig. 5 and can be slid on to the end of the 65 nozzle from one end into the required position. The plate fits tight and is prevented being pushed too far by bending it over at *h* at one end.

Fig. 6 shows a plate with a narrower slot 70 than that in Figs. 1 to 4; Fig. 7 a slot of the same width but less in length and Fig. 8 a circular hole. Various sizes of slots and holes may be employed in accordance with the work being operated upon and whether 75 more or less spreading or more or less concentration is required.

What I claim as my invention and desire to secure by Letters Patent is:—

1. In a flame spreader, the combination, 80 with a nozzle, of a detachable plate secured crosswise of the nozzle outlet and in contact with its edges, said plate being provided with an outlet opening which is of less area than the outlet opening of the nozzle 85 and being otherwise imperforate, whereby the size and shape of the flame is modified.

2. In a flame spreader, the combination, 90 with a nozzle having flanges at the edges of its outlet opening, of a slidable plate provided with flanges which engage with the flanges on the nozzle and which hold the said plate in contact with the edges of the said outlet, said plate being provided with an outlet opening of less area than the outlet 95 opening of the nozzle and being otherwise imperforate, whereby the size and shape of the flame is modified.

In testimony whereof I have hereunto set my hand in the presence of two witnesses. 100

WILLIAM SWALLOW.
